(57) **CLAIM**

The ornamental design for a vibration ring, as shown and described.

DESCRIPTION

FIG. 1 is a top perspective view of the vibration ring of the present invention.

FIG. 2 is a bottom perspective view of the vibration ring of the present invention.

FIG. 3 is a top plan view of the vibration ring of the present invention.

FIG. 4 is a bottom plan view of the vibration ring of the present invention.

FIG. 5 is a left side elevation of the vibration ring of the present invention.

FIG. 6 is a right side elevation of the vibration ring of the present invention.

FIG. 7 is a rear elevation of the vibration ring of the present invention; and,

FIG. 8 is a front elevation of the vibration ring of the present invention.

The broken lines shown in the drawings are for the purposes of illustrating portions of the vibration ring, which form no part of the claimed design.

1 Claim, 8 Drawing Sheets---
